2 SHEETS—SHEET 2.

UNITED STATES PATENT OFFICE.

LOUIS DAVID CHEVALIER AND HENRY CHARLES RECHE, OF DUBUQUE, IOWA.

ORE-CONCENTRATOR.

1,194,477.

Specification of Letters Patent. Patented Aug. 15, 1916.

Application filed December 27, 1915. Serial No. 68,791.

To all whom it may concern:

Be it known that we, LOUIS DAVID CHEVALIER and HENRY CHARLES RECHE, citizens of the United States of America, and residents of Dubuque, Dubuque county, Iowa, have invented certain new and useful Improvements in Ore-Concentrators, of which the following is a specification.

Our invention relates to improvements in apparatus for concentrating ore, and the object of our improvement is to furnish a device which shall effectively separate the heavier from the lighter ingredients of comminuted ore by the action of mechanical agitation thereof accompanied by the differential movements imparted thereto caused by the employment of air currents moving in various directions. This object we have accomplished by the mechanism which is hereinafter described and claimed, and which is illustrated in the accompanying drawings, in which:

Figure 1 is a longitudinal vertical section of our improved apparatus. Fig. 2 is a plan view of the oscillating table. Fig. 3 is a perspective view of said table. Fig. 4 is a plan view of said table with the cross-bars removed, and part of the woven-wire fabric broken away. Fig. 5 is a cross-section of said table taken on the line *c-d* of Fig. 2, and Fig. 6 is another cross-section thereof taken on the line *a-b* of Fig. 2. Fig. 7 is a detail view of portions of the cross-bars, showing their connecting-means.

Similar numerals of reference denote corresponding parts throughout the several views.

The shallow oscillatory box 1 is of the general form of an oblong with two opposite angles truncated at different degrees of obliquity, the left-hand forward angle being preferably truncated at an angle of 55 degrees, while the opposite rear angle at the right is truncated at an angle of 35 degrees, but it is to be understood that the box may be differently formed, as our invention is not dependent in any way upon the shape of the box.

Referring first to Fig. 1, the box is 50 closed at the top by two superposed spaced webs of porous material, the lowermost being preferably a piece of loosely meshed cloth 2, the upper being of woven wire 3. Immediately above these layers are arranged 55 and secured a plurality of spaced longitudinal slots or ribs 4, and upon these ribs are

arranged and secured another plurality of spaced ribs 5, of less height, but arranged at an angle of 55 degrees of obliquity relative to the length of the box. The two series of ribs 4 and 5 are secured together by means of riveted twisted plates 36, or by other suitable fastening means, as shown in Fig. 7. The box has a raised border-strip 34 at its rear and left side, the interspaces of said ribs being otherwise uninclosed at the ends, but may be so inclosed all around, if desired.

The box 1 is supported and oscillated by the following means: Pairs of bearing-lugs 70 11 and 17 are mounted respectively on the box and on a supporting surface underneath and orificed to receive pintles 12 and 18 located respectively at opposite ends of two part links 13-15, of which the parts 13 are 75 adjustably received and held in the hollows of the tubular parts 15 by set-screws 16. The left-hand parts 13 also are provided with slots 14 through which the pintles 12 pass, permitting some play as required when the 80 box is oscillated by a power-connection at that side, as hereinafter described.

A bracket 19 is fixedly mounted on the left-hand end of the box, and has an eccentric-strap 20, in which is rotatably seated 85 an eccentric 21 fixed on a horizontal shaft, the latter seated in bearings 23 on the standards 24, and carrying a belt-wheel 25 for power transmission. Underneath the left-hand end of the box 1 is located a rotary fan 90 10 having a horizontal conduit 9 carried under and to the center of the box. The bottom of the box is orificed to seat short tubes 7, and rimmed ports are provided in the conduit 9, the said rimmed ports and 95 tubes 7 being connected by flexible collapsible tubular sections 8, permitting relative motion to the box, while not interfering with the currents of air carried into the box. At opposite sides and ends of the box orifices 100 are provided to seat the lower ends of inwardly-curved tubes 6 which curve upwardly about the box to deliver over its upper surface.

The numeral 26 denotes an upwardly 105 domed cover of the same contour and located above the box 1, and having notched recesses in its depending edge to receive and permit free relative movements to the upper ends of the curved tubes 6 extending inwardly therethrough. A conduit 28 leads 110 from any source of supply to the left-hand

rear corner of the box 1, through said cover 26. At the middle of said cover is located an erect, relatively large conduit 29, bent to one side and provided with a depressed box-like part 30, with sloped bottom 32 having a slide 31 for removal of its contents.

Referring now to Figs. 3, 5 and 6, the cross-bars or ribs 4 and 5 are shown as preferably variably bent or curved so as to provide a surface contour of a somewhat dished or hollowed form with parts higher or lower respectively than other parts as requisite for the proper carriage and delivery thereover of the comminuted mixed materials while 15 under the process of separation.

At the location of cross-section *c-d*, the left-hand corner of the cross-ribbed top is elevated more than the middle of the top to induce gravity to aid in carrying the materials received from the conduit 28 toward the middle of said top. The forward portion of such top is also more elevated than the middle part, while the right hand rear corner part is considerably lower than the 20 right-hand forward corner part, for a purpose to be hereinafter described. The forward edge part of the said top is concavely medially depressed.

The apparatus is particularly designed 30 and appropriated for use in localities where there is an abundance of ore, accompanied with a scarcity of water supply.

Operation: When the comminuted ore is delivered upon the left-hand rear corner of 35 the grid composed of the cross-ribs 4-5, and the power applied to oscillate the box 1, the ore is soon carried over and spread upon the entire top of the grid filling the interspaces of the ribs. The fan being started, vertical air-currents are delivered into the box and 40 pass thence upwardly through the respective interstices of the cloth 2 and the wire netting 3. Thence the air-currents, as indicated by the arrows in Fig. 1 penetrate the layer of mixed ore and gangue particles as 45 these are moved and shaken back and forth, up and down, and tend to separate them, carrying the lighter particles of the gangue into a layer by itself relatively to a separated ore layer. The air-currents which 50 pass through the curved tubes 6 are delivered under the hood 26 over the grid, moving oppositely, toward the center, then joining the first-mentioned air-currents in moving upwardly through the pipe 29. Small 55 particles of ore which may have been carried through this pipe 29, being heavier than any accompanying small particles of gangue, tend to fall into the receptacle 30, whence they may be removed by means of the slide 60 31 in the inclined bottom 32, such lighter particles of gangue not falling but being carried away through the pipe to its delivery end. The oscillation of the grid 4-5 tends 65 to work the heavier particles toward the

lower part of the grid at its depressed right-hand rear corner, the overlying lighter particles being thus pushed over to the medially depressed front of the grid whence they fall into a chute 35, shown in Fig. 2. The relatively heavy ore particles after separating and collecting within the medial concavity of said grid are discharged along the oblique right-hand side of the grid into a chute 33. The operation of separation is greatly 70 aided by the action of the cross or horizontal air-currents delivered by the curved tubes 6 across the top of the grid. This stirs up the partially separated mass and helps to propel the overlying layer of lighter particles over 75 the raised forward part of the grid, while gravity acts on the heavier particles to draw them down to the middle and delivery parts of the grid. In the absence of the cross-currents of air mentioned, the process would be greatly lengthened and rendered less efficient. 80

The apparatus may be used to separate any heavy components from lighter materials in a mixture, such as coal from stony 85 particles, or the like, as well as ore.

Various changes may be effected in the form, arrangement or elements of the apparatus described, without, however, departing from the principles of our invention or the 90 scope of its protection.

Having described our invention, what we claim as new and desire to secure by Letters Patent, is:

1. In an apparatus of the character described, an oscillatory reticulated table, means for forcing air upwardly through its reticulations and other means for creating opposed horizontal air currents over the upper surface thereof independent of those 100 passing through the reticulations.

2. In an apparatus of the character described, an oscillatory table adapted to receive ore concentrates, separated means for forcing air currents vertically through 105 said concentrates and also in opposed horizontal currents, independent of those which pass vertically through the concentrates, across its upper surface, and an inclosure for said table provided with an air delivery 110 port.

3. In an apparatus of the character described, an oscillatory table with reticulated upper surface, and means for passing fluid currents upwardly through the reticulated 120 surface, said reticulated surface being medially concaved and depressed at one edge in communication with said concavity to facilitate the discharge of a heavier component of a concentrate moving thereupon. 125

4. In an apparatus of the character described, an oscillatory table with reticulated upper surface, and means for passing fluid currents upwardly through the reticulated 130 surface, said reticulated surface being me-

- dially concaved and depressed at each of two delivery edges in communication with said concavity, to respectively separately discharge the heavier and lighter components 5 of a concentrate moving thereupon.
5. In an apparatus of the character described, an oscillatory table in the form of a hollow box whose top is formed of reticulated material, independent means for conveying air, one means adapted to cause the passage of air vertically through the reticulated top and the other air conveying means adapted to deliver horizontal opposed currents across the top of the box.
- 10 6. In an apparatus of the character described, an oscillatory table in the form of a hollow box whose top is formed of reticulated material, cross-bars arranged upon the top of said box obliquely thereto and other cross-bars arranged upon the top of the first-mentioned cross-bars longitudinally, a conduit leading into said box, means for forcing air under pressure through said conduit, and conduits leading from said box 15 to deliver air under pressure over and across the top of said box and the cross-bars thereon in opposite directions.
7. In an apparatus of the character described, an oscillatory table in the form of a hollow box having a reticulated top covered by a network of cross-bars some of which are set obliquely to the length of the box and others set longitudinally therewith, the bars being downwardly curved 20 to provide a transverse medial depression and a depression at one part at its edge leading thereinto to separate by gravity and discharge the heavier component of mixed concentrates deposited on a raised part of said top, and means adapted to force air through concentrates moving over said top and across its upper surface.
- 25 8. In an apparatus of the character described, an oscillatory table, means for oscillating said table, a hood supported over said table and provided with a discharge conduit, said table having a reticulated top, means for forcing air upwardly through said top and conduits communicating with said means for concurrently creating opposed cross air currents over the top of the table under said hood directed angularly to the air currents ascending through said reticulated top.
- 30 9. In an apparatus of the character described, a longitudinally oscillatory jig having a series of spaced longitudinal division-contrivances therealong, and a series of spaced superposed obliquely arranged division-contrivances set across them inclined from a receiving corner of the jig toward the opposite side and corner thereof, both sets of said division-contrivances being medially concaved in a direction transverse to the direction of the obliquely arranged series thereof.
- 35 10. In an apparatus of the character described, a longitudinally oscillatory box, and a porous cover therefor, a series of spaced longitudinal bars arranged over and upon said cover, and another series of medially concaved spaced bars arranged across the first-mentioned bars in a direction angular thereto which is in the line of flow of granular substances therebetween 40 from a place of deposit on one corner of the jig.
- Signed at Waterloo, Iowa, this 23d day of November, 1915.
